COMBINED TOY AND NOISE-MAKER

Sidney A. Tarrson, 777 S. Tripp, Chicago, Ill. 60624

Filed Apr. 8, 1966, Ser. No. 1,818

Term of patent 3½ years

(Cl. D34—15)

Fig. 1.

Fig. 2.

Fig. 3.

Fig. 4.

FIG. 1 is a front elevational view of a combined toy and noise-maker showing my new design;

FIG. 2 is a side elevational view thereof, the opposite side being substantially the same;

FIG. 3 is a top plan view thereof;

FIG. 4 is a bottom plan view thereof.

I claim:

The ornamental design for a combined toy and noise-maker, as shown and described.
